UNITED STATES PATENT OFFICE

155,891

DESIGN FOR A WALL HEATER

Harry R. Greene, Pasadena, Calif., assignor, by mesne assignments, to Affiliated Gas Equipment,
Inc., Cleveland, Ohio, a corporation of Delaware

Application May 22, 1948, Serial No. 146,515

Term of patent 14 years

(Cl. D81—10)

To all whom it may concern:

Be it known that I, Harry R. Greene, a citizen of the United States, residing in Pasadena, in the county of Los Angeles, State of California, have invented a new, original, and ornamental Design for a Wall Heater, of which the following is a specification, reference being had to the accompanying drawing, forming a part thereof.

I claim:

The ornamental design for a wall heater, as shown.

HARRY R. GREENE.
